UNITED STATES PATENT OFFICE.

ISAAC STRIPE, OF AULTMAN, OHIO.

SHIPPING-CRATE.

SPECIFICATION forming part of Letters Patent No. 762,102, dated June 7, 1904.

Application filed July 15, 1903. Serial No. 165,562. (No model.)

To all whom it may concern:

Be it known that I, ISAAC STRIPE, a citizen of the United States, residing at Aultman, in the county of Stark and State of Ohio, have 5 invented certain new and useful Improvements in Shipping-Crates; and I do hereby declare that the following is a full, clear, and exact description of the same, reference being had to the annexed drawings, making a part of this 10 specification, and to the figures of reference marked thereon, in which—

Figure 1 is a perspective view showing the top or cover elevated in dotted lines and closed in full lines. Fig. 2 is a section cut through 15 at a point where one of the retaining-wires is located.

The present invention has relation to shipping-crates; and it consists in the different parts and combination of parts hereinafter 20 described, and particularly pointed out in the claim.

The object of the present invention is to provide a shipping-crate that will be light, 25 easy of construction, and cheap, so that the same may be destroyed at the end of its destination without adding increased cost and saving the return express or freight charges.

Similar numerals of reference indicate corresponding parts in both figures of the drawings.

In the accompanying drawings, 1 represents the end rectangular frames, which are formed of a size to correspond with the size of the crate designed to be constructed, except 35 of course as to its length. The corners of the end frames 1 are mitered, as illustrated in Fig. 1, and the corners are so formed or connected for the purpose hereinafter described.

The wires 2 are each formed of a single 40 piece and are bent when brought into their normal position in substantially rectangular form. The corner side bars 3 are strung upon the wires 2, as illustrated in Fig. 2, and nails driven through said side bars at substantially 45 right angles to each other, as illustrated in dotted lines, Fig. 2, by which arrangement the ends of the rectangular end frames are connected together and side bars connected to the rectangular frame, thereby providing an easy 50 and cheap manner of attaching the different parts together.

For the purpose of closing the sides of the crate and also the bottom thereof thin strips of wood 4 may be attached by nails or otherwise to the end frames 1, or bars, such as 3, 55 may be strung upon the wires 2 and spaced so as to form the sides and bottom of the crate.

In forming the crates for different articles in some instances it may be necessary to have the sides and bottoms nearly closed or altogether closed, and in other instances side bars, such as 3, may be employed and space left between the bars.

It will be understood that by my peculiar arrangement the wires 2 will allow the sides 65 and bottoms of the crate to be brought into proper position to be attached to the end frames 1 and at the same time the cover-bars 5 strung upon the wires 2, by which arrangement the crate is inclosed upon all sides and 70 its top.

The cover proper or lid can be removed or turned back, bending the wires 2, constituting the hinge for the cover, and when the wires are brought down so as to bring the 75 cover-bars 5 upon the end frames 1 they may be nailed; but if in the event it is not necessary to nail the covers the wires 2 may be bent over the cover-bars 5, as illustrated at 6, or said wires may be bent over after the 80 bars 5 have been nailed.

It will be understood that by my peculiar arrangement the crate is easily made and is cheap, thereby providing an inexpensive manner of shipping various kinds of vegetables 85 and fruit.

To the end frames 1, and preferably upon the inner sides thereof, are attached the sections or boards 7, or slats may be employed, if desired.

For the purpose of strengthening the end frames cross-wires, such as 8, may be employed and preferably are employed, which wires are simply connected at their ends to the different members of the end frames 1.

Having fully described my invention, what I claim as new, and desire to secure by Letters Patent, is—

The combination of end frames, wire bodies surrounding the crate and of a form to correspond with the form of the crate in cross-section, a series of bars having the wires extend-

ed therethrough, said bars adjustable upon the wires, strips secured to the end frames and the wires located over the strips and the wires carrying the bars constituting the hinge 5 of the crate-cover, substantially as and for the purpose specified.

In testimony that I claim the above I have

hereunto subscribed my name in the presence of two witnesses.

ISAAC STRIPE.
